UNITED STATES PATENT OFFICE.

JOHN L. NYE, OF OELRICH'S, SOUTH DAKOTA.

CUFF-LINK GUARD.

1,226,577.

Specification of Letters Patent. Patented May 15, 1917.

Application filed June 6, 1916. Serial No. 101,990.

To all whom it may concern:

Be it known that I, JOHN L. NYE, a citizen of the United States, residing at Oelrichs, in the county of Fall River and State 5 of South Dakota, have invented new and useful Improvements in Cuff-Link Guards, of which the following is a specification.

This invention relates to certain novel and useful improvements in guards for link buttons of cuffs.

In carrying out the present invention, it is my purpose to provide a guard which may be quickly and conveniently applied to the cuff and secured in the buttonhole thereof 15 and which will engage the post of the cuff link so as to prevent accidental disconnection of the cuff link from the cuff.

With the above and other objects in view, the invention consists in the construction, 20 combination and arrangement of parts hereinafter set forth in and falling within the scope of the claim.

In the accompanying drawing:

Figure 1 is a perspective view of a cuff 25 equipped with a cuff link guard constructed in accordance with the present invention.

Fig. 2 is a similar view of the guard removed from the cuff.

Fig. 3 is a sectional view through the 30 guard.

Fig. 4 is a plan view of the guard.

Referring now to the drawing in detail, 1 designates a substantially U-shaped clasp. Mounted in the clasp 1 is a substantially U-shaped spring 2. One leg of the spring is 35 fixed to the corresponding leg of the clasp, while formed in the other leg of the clasp is a slot 3 and pivoted in the slot 3 at the outer end thereof is a lever 4 having the 40 pivoted end formed with a right angularly projecting lug 5 adapted to bear against the adjacent leg of the spring 2 so as to force such leg of the spring toward the other leg when the lever 4 is swung into the slot 3. 45 On the other hand, when the lever is swung in the reverse direction, the leg of the spring 2 is relieved of the influence of the lug so that such leg may move away from the other leg to open the clasp. In the present in-

stance, the outer end of the lug 5 is formed 50 with a teat 6 that works in a slot 7 formed in the spring.

In accordance with my present invention, the central portion of the clasp 1 is formed with an outwardly projecting guard arm 8 55 that has its outer end portion bent at right angles to itself as at 9 and then bent again at right angles to the portion 9 as at 10. The end of the bent portion 10 is spaced apart from the central member of the clasp 60 so that the post of the link may be inserted in the hook-like arm. The outer end of the lever 4 is formed with an outwardly projecting finger 11 designed to overlie the space between the end of the hook-like arm and the 65 body of the clasp so as to close such space and prevent the accidental disconnection of the clasp from the post to the button.

In practice, the post of the cuff link is passed through the buttonholes in the cuff, 70 as usual. One leg of the clasp 1 is now slipped through one of the buttonholes in the cuff so that the legs of the clasp may be disposed upon the respective sides of the cuff. The post of the cuff button is now 75 slipped through the space between the end of the hook-like arm and the clasp and into such hook-like arm, and the lever swung into the slot 3, thereby actuating the spring 2 to clamp the cuff and the finger 11 to close the 80 space between the end of the hook-like arm and the body of the clasp. Thus, the cuff link is locked to the cuff.

I claim:

A cuff link guard comprising a substantially U-shaped clasp engaging the cuff at the button hole therein, means for locking said clasp to the cuff, a hook like arm integral with said clasp to receive the post of the link and extending across the button 85 hole, and means on said first named means cooperating with said hook-like arm to close the clasp in the hook whereby accidental disconnection of the hook like arm from the post is prevented. 90

95 In testimony whereof I affix my signature.

JOHN L. NYE.
